APPARATUS FOR PRODUCING CARBON
BLACKRobert Boyce Takewell, Borger, Tex., assignor to
J. M. Huber Corporation, Locust, N. J., a corporation of New Jersey

Application October 15, 1949, Serial No. 121,535

20 Claims. (Cl. 23—259.6)

1

This invention relates to apparatus for producing carbon black by the channel process and particularly to improvements in the apparatus to cause it to produce higher yields of carbon black.

The commercial method for the production of carbon black by the channel process involves the use of an elongated burner house provided with a plurality of spaced openings in the sides near the bottom for the admission of air and a plurality of spaced openings in the top for the escape of the gaseous products of combustion. Such burner house is provided in the upper half with a plurality of spaced channel irons extending lengthwise of the house for substantially its entire length. The channel irons are supported on a carriage which is reciprocated longitudinally of the burner house and carries the channel irons with them. Hoppers extend across the burner house below the channel irons and are spaced longitudinally of the house in accord with the amplitude of the reciprocation of the channel irons. Scrapers are positioned in the center of the hoppers and bear upon the channel irons so that as the channel irons are reciprocated, the carbon is scraped off therefrom and falls into the hoppers from the bottom of which it is removed by screw conveyors. Burner pipes are positioned under the channel irons and parallel thereto and extend for the distance between the hoppers. A suitable gas distributing system is provided to supply gas to the burner pipes. The burner pipes are provided with a plurality of spaced burner tips through which the gas is emitted and burned. The burner tips and burner pipes are so positioned below the channel irons that the flames from the burner tips impinge upon the channel irons and deposit carbon thereon.

In the operation of such apparatus, it has been noted that the flames flicker and wobble and it has also been recognized that if such flickering and wobbling of the flames could be prevented, the yield of carbon could be substantially increased. Various devices have been suggested for reducing the air currents in the vicinity of the flames so as to cause such flames to burn quietly and steadily and produce the maximum amount of carbon. However, none of such devices has been entirely successful in this respect. The most successful of which applicant is aware are the air guides of Patent 2,446,351 granted to Williams et al. on August 3, 1948. However, these air guides of Williams et al. have not been entirely successful in eliminating the disturbing

2

air currents close to the collecting hoppers which affects at least two burner tips at the ends of each burner pipe so that little carbon is produced by the flames from such tips.

5 It is an object of the present invention to provide apparatus for producing carbon black by the channel process which effectively steadies all of the flames and particularly those adjacent the collecting hoppers. Another object is to provide the conventional channel black producing apparatus with devices which more effectively controls the air currents in the vicinity of the flames and which particularly eliminates disturbing air currents adjacent the collecting hoppers. A further object is to provide devices which can be employed in combination with the apparatus of Patent 2,446,251 of Williams et al. to still further improve the yields of carbon black. A still further object is to provide apparatus and devices of the aforementioned character which are economical to produce, install and repair. Other objects are to advance the art. Still other objects will appear hereinafter.

The above and other objects may be accomplished in accordance with my invention which comprises providing vertical flat sheet metal side curtains between the walls of the burner house and the channel members adjacent such walls and spaced about 2 inches to about 6 inches from the outer edges of the channel members nearest the walls of the burner house and which side curtains extend parallel to such channel members for substantially the full length thereof and extend downward from about the level of the channel members for a distance of from about 2 to about 4 feet, and also providing 1 to 5 vertical flat sheet metal cross curtains between each two adjacent hoppers substantially parallel to the hoppers and spaced from each other and from the adjacent hoppers so that the cross curtain nearest each hopper is spaced therefrom by at least 8 inches and no more than two-thirds the distance to the adjacent hopper, said cross curtains extending across the burner house substantially from one side curtain to the other side curtain and downward from substantially immediately below the burner pipes for at least two feet.

I have found that, by providing the conventional burner house with such combination of side curtains and cross curtains, the disturbing air currents in the vicinity of the flames, including the flames adjacent the collecting hopper, are largely eliminated and the yield of carbon is substantially increased. When curtains

of the preferred number and size are employed, the increase in yield of carbon is of the order of 20% to 22%. Such combination of side curtains and cross curtains may also be employed in combination with the air-guides of Patent 2,446,351 to Williams et al. to further increase the yield of carbon black by as much as 11.5%; the yield, obtained by the combination of air-guides and curtains, being up to 35.5% greater than can be obtained without the air-guides or curtains.

My invention will be more readily understood from the detailed description hereinafter given when taken with the accompanying drawings in which:

Fig. 1 is a vertical sectional view taken longitudinally of a burner house on the line of 1—1 of Fig. 2 showing only those parts of the conventional burner house and apparatus for producing carbon black by the channel process as is necessary for an understanding of my invention and containing an illustrative embodiment of the side curtains and cross curtains of my invention;

Fig. 2 is a vertical sectional view taken cross-wise of the burner house on the line 2—2 of Fig. 1;

Fig. 3 is a vertical sectional view similar to that of Fig. 1 and illustrating a second embodiment of my invention, with the scrapers omitted;

Fig. 4 is a vertical sectional view similar to Figs. 1 and 3 illustrating a third embodiment of my invention;

Fig. 5 is a segmental view of Fig. 2 with the addition of air guides corresponding to those disclosed in Figs. 2 to 5 of Patent 2,446,351 of Williams et al.

Referring first to Figs. 1 and 2, the walls of the burner house are indicated at 10 and are provided with the conventional slotted openings for the admission of air near the base thereof at 12. The burner house is provided with the conventional channel irons 14 supported on the conventional reciprocating carriage, not shown. Carbon collecting hoppers 16 extend across the burner house and are spaced along the length of the burner house below the channel irons in the usual manner. These hoppers 16 open into a suitable conduit 18 provided with a screw conveyor 20 for removing the carbon black from the burner house. Scrapers 22 are positioned below the channel irons 14 intermediate the walls of the hoppers and bear against the lower surfaces of the channel irons for the purpose of scraping carbon therefrom. Each scraper is connected to an end of a pivoted lever 24 by a suitable supporting rod 26 and are held against the bottom of the channel irons by means of weight 28 on the other end of the lever 24.

A burner pipe 30 is spaced below each channel iron between the hoppers and extends parallel to the channel iron. Each burner pipe is provided with a plurality of spaced burner tips 32 for emitting the gas to be burned in small flames impinging on the channel irons. Each set of burner pipes is supplied with gas through a distributing pipe 34 which is in turn connected with a gas main 36 through a riser pipe 38. The structure so far described with respect to Figs. 1 and 2 is representative of the conventional form of apparatus for producing carbon black by the channel process and it may be varied as is usual in the art. It will also be understood that the burner house contains other conventional apparatus such as a reciprocating carriage for the channel irons, a table for supporting the carriage and upon which the carriage runs, etc., the details of which are not pertinent or necessary to an un-

derstanding of my invention and hence have not been shown.

In Figs. 1 and 2, I have disclosed one embodiment of my invention comprising side curtains 40 and cross curtains 42. The side curtains 40 are constructed of flat sheet metal and extend vertically between each wall 10 of the burner house and the channel irons 14 nearest such wall of the burner house and spaced about 2 inches from the outer edge of the channel member. These side curtains extend parallel to the channel members for substantially the full length thereof and the side curtains at each side may be made of one continuous piece extending the full length of the channel member or may be made up of a number of shorter sections as shown in Figs. 1 and 2 which in combination extend for the full length of the channel members. The side curtains can be made up of a number of sections of intermediate lengths as desired. Also, the side curtains may be spaced from the outer edges of the outside channel members by a distance of from about 2 inches to about 6 inches but preferably will be spaced therefrom by about 2 to about 3 inches. The side curtains extend downward from about the level of the channel members for a distance of from about 2 feet to about 4 feet, the channel members usually being about 4½ to about 6 feet above the floor of the burner house. Usually, they will extend downward for about 2 feet but a slight added advantage may be gained by extending them downward to a distance of halfway to the floor. They should not extend down to the floor of the burner house so as to obstruct the air entering the opening 12 in the walls of the burner house. The side curtains may also extend above the level of the channel members to any desired height but without advantage. As shown, the side curtains extend from substantially the center of one hopper to substantially the center of the other hopper and are supported thereon by means of bolts 44 as shown, but may be supported in any other suitable manner or to any other suitable part of the burner house or other structure therein.

A cross curtain 42 is positioned substantially halfway between each two adjacent hoppers and extends vertically substantially parallel to the hoppers. It is made of flat sheet metal. The single cross curtain may be positioned anywhere within the middle third of the distance between the hoppers and still be effective but produces the maximum effect when positioned substantially as shown. The cross curtain 42 also extends substantially from one side curtain 40 to the opposite side curtain 40. The top of the cross curtain is positioned substantially immediately below the burner pipe and extends downwardly therefrom for about 4 feet. The cross curtain 42 may extend downwardly for a lesser distance up to 2 feet and for any greater distance desired and permitted by the distance of the burner pipes to the floor of the burner house and the other apparatus contained therein. As shown, the cross curtain 42 is supported from two or more of the burner pipes by hooks 46. Other means for supporting the cross curtains 42 from the burner pipes or other structures in the burner house may be employed as desired.

Fig. 3 is similar to Fig. 1 but discloses the use of two cross curtains 42 extending downwardly from the burner pipes for about 3 feet and spaced substantially equidistant from each other and from the hoppers 16 so as to divide the area between the hoppers into 3 areas of about equal

size. These cross curtains 42 may also extend downwardly for a distance of from 2 feet to the floor of the burner house. These cross curtains 42 also extend from substantially one side curtain 40 to substantially the other side curtain 40. Otherwise, the structure shown in Fig. 3 is the same as that shown in Figs. 1 and 2.

Fig. 4 discloses structure the same as that in Figs. 1, 2 and 3 except that, in this case, there are three cross curtains 42 extending downward from the burner pipes for a distance of about 2 feet. As in the case of the other embodiments, these three cross curtains may all extend downward further, even to the floor of the burner house. It is not necessary that all of the cross curtains extend downward for the same distance but some may extend downward further than others and all of them must extend downward for at least 2 feet. As in the other embodiments of my invention, these cross curtains will extend substantially from one side curtain to the opposite side curtain.

Fig. 5 illustrates the use of the side curtains 40 and cross curtains 42 in combination with air-guides 48 constructed as shown in Figs. 2 to 5 of Patent 2,446,351. Other types of air-guides disclosed in such patent may also be employed in combination with my side curtains and cross curtains. When my cross curtains and side curtains are employed with such air-guides, they may be hung from the gas distributing pipe 34 by means of their hooks 46 or, if desired, they may be hung from the burner pipes 30 by employing hooks having a shank of sufficient length to position the tops of the cross curtains immediately below the air-guides 48. Also, in Fig. 5, I have shown the side curtains 40 as being supported from the wall 10 of the burner house by means of a bracket 50.

The side curtains 40 and cross curtains 42 of my invention are conveniently made of iron but may be constructed of any metal which will withstand the temperatures in the burner house, such as steel, aluminum, ferrous alloys, chromium alloys, nickel alloys and the like.

It will be understood that the embodiments shown in the drawings are given for illustrative purposes solely and that my invention is not limited to such specific embodiments. The vertical extents of the cross curtains and side curtains may be varied as desired within the limits hereinbefore set forth. While I preferably employ from 1 to 3 cross curtains, the number thereof can be increased to 5 without disadvantage but with very little advantage. An even larger number of cross curtains could be employed but without advantage and such larger number would generally be impractical. When from one to three cross curtains are employed, the best results will generally be obtained when the distance to which they extend downward from the burner pipes is substantially equal to that represented by the formula

$$\frac{D}{N+1}$$

wherein D represents the distance between the adjacent hoppers and N is the number of cross curtains between such hoppers. Generally, the shorter the distance the cross curtains extend downward, the more curtains are required to produce the maximum effect.

To illustrate the advantage of the apparatus of my invention, a commercial burner house of conventional type, provided with the usual channels, burner pipes, collecting hoppers and the like, was equipped with various combinations of

side curtains, cross curtains and air-guides and the amount of carbon produced was determined. In this burner house, the channel irons were 5½ feet above the floor of the burner house and the adjacent collecting hoppers were spaced apart by about 7 feet. The number of pounds of carbon produced by the burner house per hour, before being equipped with the curtains, etc., was also determined. When only one cross curtain was employed between adjacent hoppers, it was located midway between them as shown in Fig. 1. When three cross curtains were employed between adjacent hoppers, they were spaced as in Fig. 4. The number of cross curtains and the distances to which they extended downward from the burner pipes; the number of side curtains, the distances they extended downward from the level of the channel irons and their distances from the outside edge of the channels nearest the walls of the burner house; and the results obtained without the curtains, with various curtains and combinations of curtains and when employed with the air-guides of Fig. 5 of Patent 2,446,351 are disclosed in the following table.

Table

	Type and number of curtains	Pounds carbon per hour	
30	None	14.35	
1	One 4 ft. cross curtain	13.25	
2	One 2 ft. cross curtain	14.10	
3	Three 4 ft. cross curtains	15.90	
4	No cross curtains and 2 ft. side curtains 2 inches from channels	15.50	
35	5	One 4 ft. cross curtain and 2 ft. side curtains 2 in. from channels	17.45
6	Three 4 ft. cross curtains and 2 ft. side curtains 2 in. from channels	17.75	
7	One 2 ft. cross curtain and 2 ft. side curtains 2 in. from channels	17.00	
8	One 1 ft. cross curtain and 2 ft. side curtains 2 in. from channels	15.90	
40	9	Three 2 ft. cross curtains and 2 ft. side curtains 2 in. from channels	16.90
10	One 4 ft. cross curtain and 1 ft. side curtains 2 in. from channels	14.90	
11	One 4 ft. cross curtain and 3 ft. side curtains 2 in. from channels	17.50	
45	12	One 4 ft. cross curtain and 2 ft. side curtains 6 in. from channels	15.40
13	One 4 ft. cross curtain and 2 ft. side curtains 12 in. from channels	13.35	
14	One 4 ft. cross curtain and 2 ft. side curtains 2 ft. from channels and burner pipes provided with air-guides such as Fig. 5 of U. S. P. 2,446,351	19.45	
50	15	Provided with air-guides of Fig. 5 of U. S. P. 2,446,351 only	17.45

From this table, the effectiveness of the combination of side curtains and cross curtains is evident. When the burner house was provided with one 4 ft. cross curtain and 2 ft. side curtains (No. 5), the yield of carbon was increased from 14.35 pounds per hour to 17.45 pounds per hour, an increase of 3.1 pounds per hour or a 21.6% increase in the yield. The air-guides of Patent 2,446,351, when employed alone (No. 13), produced a corresponding increase. However, the use of one 4 ft. cross curtain and 2 ft. side curtains in combination with such air-guides further increased the yield by 2 pounds or 11.5%; the combination of air-guides and curtains producing a total increase in yield of 5.10 pounds or 35.5% over that obtained in the absence of the curtains and air-guides.

Figs. 3 and 4 show two and three cross curtains, respectively, spaced substantially equidistant from each other and from the adjacent hoppers, which spacing produces the maximum effect. When four or five or more cross curtains are employed, the maximum effect is obtained when they are spaced substantially equidistant

from each other and from the adjacent hoppers. However, different spacing will also provide a beneficial effect provided that no cross curtain is placed materially less than 8 inches from a hopper and the cross curtain nearest to a hopper is not spaced therefrom by more than two-thirds the distance between the hoppers. When two cross curtains are used, the cross curtain nearest each hopper may be spaced from such hopper by about 8 inches, preferably about 12 inches or more. Additional cross curtains may be positioned between such two cross curtains in any desired manner. The cross curtains will usually be spaced from each other by at least 8 inches, preferably, at least 12 inches. If two or more cross curtains are spaced materially less than 8 inches from each other, their effect will be substantially equal to that of a single cross curtain.

It will thus be apparent that I have provided new and improved apparatus for producing carbon black by the channel process whereby the yield of carbon black can be very greatly increased. This increase in yield is obtained without deleterious effects on the quality of the carbon black. These side curtains and cross curtains of my invention may be readily and economically manufactured and installed in the conventional burner houses and repaired, because of their simple construction. Thereby, the yield of carbon black in conventional burner houses can be greatly increased at comparatively small cost. This increase in yield is of economic importance. The higher yields of carbon black mean a corresponding decrease in the cost of producing carbon black. Also, the higher yields require a lesser amount of gas to produce a desired amount of carbon black resulting in a substantial conservation of natural gas which is an important natural resource. Therefore, it will be apparent that my invention constitutes a valuable advance and contribution to the art.

I claim:

1. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 5 vertical flat sheet metal cross curtains between each two adjacent hoppers substantially parallel to the hoppers and spaced substantially equidistant from each other and from the adjacent hoppers, said cross curtains extending substantially from one side curtain to the opposite side curtain and downward from substantially immediately below the burner pipes for at least two feet.

2. Apparatus for producing carbon black by the impingement process which comprises a burner house containing a plurality of horizontally disposed channel members extending for substan-

5 tially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced substantially equidistant from each other and from the adjacent hoppers, said cross curtains extending substantially from one side curtain to the opposite side curtain and downward from substantially immediately below the burner pipes for at least two feet.

25 3. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for a distance substantially equal that represented by the formula

$$55 \quad \frac{D}{N+1}$$

wherein D is the distance between the adjacent hoppers and N is the number of cross curtains between such hoppers.

60 4. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially

the full length thereof and extending downward from about the level of the channel members for a distance of from about 2 to about 4 feet, and 1 to 5 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

5. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

6. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for a distance substantially equal that represented by the formula

$$\frac{D}{N+1}$$

wherein D is the distance between the adjacent hoppers and N is the number of cross curtains between such hoppers.

7. Apparatus for producing carbon black by the impingement process which comprises a burner house containing a plurality of horizontally dis-

posed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 feet to about one-half the distance from the channel members to the floor of the burner house, and 1 to 5 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

8. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 feet to about one-half the distance from the channel members to the floor of the burner house, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

9. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 feet to about one-half the distance from the channel

members to the floor of the burner house, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for a distance substantially equal that represented by the formula

$$\frac{D}{N+1}$$

wherein D is the distance between the adjacent hoppers and N is the number of cross curtains between such hoppers.

10. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of from about 2 feet to about one-half the distance from the channel members to the floor of the burner house, and 1 to 5 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

11. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of from about 2 feet to about one-half the distance from the channel members to the floor of the burner house, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

12. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of from about 2 feet to about one-half the distance from the channel members to the floor of the burner house, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for a distance substantially equal that represented by the formula

$$\frac{D}{N+1}$$

wherein D is the distance between the adjacent hoppers and N is the number of cross curtains between such hoppers.

13. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of about 2 feet, and 1 to 5 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

14. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet

metal side curtains spaced about 2 inches from the outer edges of the channel members nearest the walls of the burner house and extending parallel to such channel members for substantially the full length thereof and extending downward from about the level of the channel members for a distance of about 2 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for at least two feet.

15. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of about 2 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from substantially immediately below the burner pipes for a distance substantially equal that represented by the formula

$$\frac{D}{N+1}$$

wherein D is the distance between the adjacent hoppers and N is the number of cross curtains between such hoppers.

16. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches from the outer edges of the channel members nearest the walls of the burner house and extending parallel to such channel members for substantially the full length thereof and extending downward from about the level of the channel members for a distance of about 2 feet, and 1 to 3 vertical flat sheet metal cross curtains between each two adjacent hoppers substantially parallel to the hoppers and spaced equidistant from each other and from the adjacent hoppers, said cross curtains extending substantially from one side curtain to the opposite side curtain and downward from

substantially immediately below the burner pipes for about 4 feet.

17. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 5 vertical flat sheet metal cross curtains between each two adjacent hoppers substantially parallel to the hoppers and spaced from each other and from the adjacent hoppers, said cross curtains extending substantially from one side curtain to the opposite side curtain and downward from substantially immediately below the burner pipes for at least two feet, the cross curtain nearest each hopper being spaced therefrom by at least 8 inches and no more than two-thirds the distance to the adjacent hopper.

18. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 5 vertical flat sheet metal cross curtains between each two adjacent hoppers substantially parallel to the hoppers and spaced from each other and from the adjacent hoppers by at least 8 inches, said cross curtains extending substantially from one side curtain to the opposite side curtain and downward from substantially immediately below the burner pipes for at least two feet, the cross curtain nearest each hopper being spaced therefrom by no more than two-thirds the distance to the adjacent hopper.

19. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across the burner house, vertical flat sheet metal side curtains spaced about 2 inches to about 6 inches

from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced from each other and from the adjacent hoppers, said cross curtains extending substantially from one side curtain to the opposite side curtain and downward from substantially immediately below the burner pipes for at least two feet, the cross curtain nearest each hopper being spaced therefrom by at least 8 inches and no more than two-thirds the distance to the adjacent hopper.

20. Apparatus for producing carbon black by the impingement process which comprises a burner house containing a plurality of horizontally disposed channel members extending for substantially the length thereof, a burner pipe spaced below each channel member and extending parallel to the channel member, a plurality of burner tips in the upper surface of each burner pipe, a plurality of carbon collecting hoppers spaced along the length of the burner house below the channel members, each hopper extending across

the burner house, vertical flat sheet metal side curtains spaced about 2 inches to about 6 inches from the outer edges of the channel members nearest the walls of the burner house and extending parallel to such channel members for substantially the full length thereof and extending downward from about the level of the channel members for a distance of from about 2 to about 4 feet, and 1 to 3 vertical flat sheet metal cross curtains between each two adjacent hoppers substantially parallel to the hoppers and spaced from each other and from the adjacent hoppers by at least 8 inches, said cross curtains extending substantially from one side curtain to the opposite side curtain and downward from substantially immediately below the burner pipes for at least two feet, the cross curtain nearest each hopper being spaced therefrom by no more than two-thirds the distance to the adjacent hopper.

ROBERT BOYCE TAKEWELL.
